H. M. STRAWN,
WOOD HANDLING DEVICE,
APPLICATION FILED FEB. 26, 1919.

1,343,288.

Patented June 15, 1920.

UNITED STATES PATENT OFFICE.

HERMAN M. STRAWN, OF CHICO, CALIFORNIA.

WOOD-HANDLING DEVICE.

1,343,288.

Specification of Letters Patent. Patented June 15, 1920.

Application filed February 26, 1919. Serial No. 279,331.

To all whom it may concern:

Be it known that I, HERMAN M. STRAWN, a citizen of the United States, residing at Chico, in the county of Butte and State of California, have invented certain new and useful Improvements in Wood-Handling Devices, of which the following is a specification, reference being had to the accompanying drawings.

10 This invention relates to an improved wood handling device.

Heretofore it has been found that the handling of wood a stick at a time, is exceedingly slow and laborious, making the labor practically so costly that the wood was substantially not worth the cost of producing and delivery.

Therefore, the invention aims to provide an improved apparatus, particularly such 20 as a pair of cradle frames for the reception of the wood, whereby it may be carried conveniently from the woodyard to the consumer's residence.

The invention further aims to provide a 25 pair of cradle frames, to be so positioned in spaced relation to each other, as to permit the wood to be piled thereon, in combination with means, whereby the two cradle frames may be hoisted, and swung upon the

30 truck for delivery.

Also, heretofore in piling wood by building bulk-heads (which is accomplished by piling the wood one layer cross-wise and the next layer at right angles thereto) the 35 party doing the work could very often give dishonest measure by leaving a vacant space on the interior of the pile.

It is the aim of the present invention to provide a pair of cradle frames having 40 means carried thereby, for contacting the pile of wood (which is arranged on the two cradle frames), thereby preventing the workman from leaving the vacant space or hollow on the interior of the pile.

45 The invention further aims to provide cradle frames which are extensible or collapsible, and means for holding the parts extended and in position, in combination with means for handling the cradle frames from 50 the truck at the curb, to the basement of the residence, this latter means comprising a handcar, which may be easily wheeled from the curb to the basement or to a window leading to the basement.

55 While the present design and the construction of the invention is deemed prefer-

able, it is obvious that changes may be made in the details, when reducing the device to a practical form for commercial purposes. The right to these changes is claimed, provided they are comprehended within the scope of what is claimed.

The invention comprises further features and combination of parts as hereinafter set forth, shown in the drawings and claimed.

In the drawings:

Figure 1 is a view in perspective of the wood handling cradle frame constructed in accordance with the invention.

Fig. 2 is a view in elevation of the cradle frame, showing a pile of wood on the cradle frame, and the means for drawing the wood into a compact form under tension, the pile of wood being illustrated in elevation.

Fig. 3 is a perspective view on one of 75 the cradle frames collapsed.

Referring to the drawings 1 and 2 designate a pair of cradle frames, which, when in use, are arranged in spaced parallel relation as illustrated, for the reception of the 80 wood in a pile. Each cradle frame comprises a base beam 3, and the end vertical posts 4 and 5, hingedly connected at 6 to the base beam. By the arrangement of the 85 hinges in the manner illustrated, the vertical posts 4 and 5 may be collapsed upon and against the base beam 3 as shown in Fig. 4. However, when the cradle frames are in use the vertical posts 4 and 5 when disposed in operative position, are 90 reinforced by the bracing links 7. These bracing links are connected to the base beams as shown at 8, and are in turn detachably connected to the vertical posts as 95 shown at 9. In order to hold the cradle frames parallel and spaced, as desired, transverse rods 10 are connected at 11 to the base beam of the cradle frame 2. These rods 10 are in turn connected detachably to the base beam 3 of the cradle frame 1, 100 as shown at 12. These detachable connections 9 and 12 consist of screws passing through the ends of the rods 7 and 10. It is obvious that the braces may be disconnected from the upright posts 4, allowing 105 them to be collapsed against the base beam.

Loosely fitting over the upper ends of the upright posts 4 and held in position by the staples 13 are loops 14, to which the rods 15 are connected. The opposite ends of the 110 rods 15 have elongated loops 16, which are designed to fit loosely over the upright posts

5. Pivots mounted upon the upper ends of the upright posts 5 as indicated at 17 are levers 18, which are provided with hook portions 19. When the wood is being piled 5 upon the two cradle frames the rods 15 are tilted and moved backwardly out of position, the loops 16 having been disconnected from the upright posts 5. However, after a sufficient pile of wood is arranged upon the 10 cradle frames, these rods 15 may be positioned over the pile. The loops 16 are then connected to the hooks 19 of the levers 18. It is obvious that after so connecting the loops 16, the levers 18 may be moved upon 15 their pivots, thereby drawing the upright posts 4 and 5 toward each other at their upper ends. In other words, the structure is drawn tight and rigid, the loops 16 being put under tension.
- 20 Threaded into the adjacent edges of the base beams, and the adjacent edges of the upright posts 4 and 5 are screw eyes 20. Connected to the screw eyes is a plurality of short chains 21 of general construction.
- 25 The outer ends of these chains are provided with rings 22. Cables or the like 23 of any suitable length are passed through the rings 22, in the manner shown, and the opposite ends of the cables are brought together, and 30 are provided with rings 24. The rings 24 are designed to be arranged in close position, and to be engaged by a suitable unitary hoisting hook 25 carried by any suitable hoisting mechanism (not shown). After the 35 wood is arranged in a pile upon the cradle frames, the rings 24 are brought closely together and in engagement with the hook 25. The cradle frame is then lifted, and in so lifting the same the cables are drawn tight 40 about the pile of wood, it being obvious that it is impossible for the workman to leave a vacant space on the interior of the pile. After the cradle has been hoisted and placed upon a truck (not shown), and delivered to 45 the consumer's residence, a handcar (not shown) may be employed, for wheeling the cradle to the basement, where the pile of wood may be arranged.

The invention having been set forth, what 50 is claimed as new and useful is:

1. In a wood handling device, the combination with a pair of collapsible cradle frames, of means for holding the cradle frames in spaced parallelism to each other, each cradle frame comprising a base beam and a pair of end uprights hingedly connected to the ends of the base beams, whereby by the uprights may be collapsed against the base beam, means for holding the uprights 55 extended vertically, detachable tie connections between the upper ends of the uprights and means flexibly connected to the base beam and the uprights for drawing a pile of wood compact in the cradle frames.
- 60 2. In a wood handling device, the combi-

nation with a pair of collapsible cradle frames, of means for holding the cradle frames in spaced parallelism to each other, each cradle frame comprising a base beam and a pair of end uprights hingedly connected to the ends of the base beams, whereby by the uprights may be collapsed against the base beam, means for holding the uprights extending vertically, detachable tie connections between the upper ends of the uprights 75 and means carried by the base beam and the uprights for drawing a pile of wood compact in the cradle frames, said last mentioned means comprising screw eyes carried by the base beams and the uprights, short 80 loose chains loosely connected to the screw eyes and having their outer ends provided with rings, cables passing through the rings of the short chains and having rings at their opposite ends to be brought together for engagement with a hoisting hook.

3. In a wood handling device, the combination with a pair of cradle frames, of means for holding the same in spaced parallelism, said cradle frames having end uprights, screw eyes carried by the cradle frames, short chains loosely connected to the screw eyes and provided with rings at their outer ends, and cables passing through the rings of the chains, and having rings at their 90 opposite ends to be brought together to engage a unitary hoisting hook.

4. In a wood handling device, the combination with a pair of cradle frames, of means for holding the same in spaced parallelism, said cradle frames having end uprights, screw eyes carried by the cradle frames, short chains loosely connected to the screw eyes and provided with rings at their outer ends, and cables passing through the 100 rings of the chains and having rings at their opposite ends to be brought together to engage a unitary hoisting hook, and tie connections between the upper end of the cradle frames.

5. In a wood handling device, the combination with a pair of cradle frames, of means for holding the same in spaced parallelism, said cradle frames including uprights at their ends, a plurality of flexible means 110 connected to the inner edges of the bases of the cradle frames and the inner edges of the uprights and pliable strands loosely and slidably passing through the ends of the flexible means and having their opposite 115 ends provided with eyes brought together to engage a unitary hoisting member.

6. In a wood handling device, the combination with a pair of cradle frames, of means for holding the same in spaced parallelism, said cradle frames including uprights at their ends, a plurality of flexible means connected to the inner edges of the bases of the cradle frames and the inner edges of the uprights and pliable strands loosely and 125 130

slidably passing through the ends of the flexible means and having their opposite ends provided with eyes brought together to engage a unitary hoisting member, wire connectors connected to corresponding uprights, the other ends of the wire connectors terminating in loops, and pivoted slotted levers to engage said loops, to detachably con-

nect the wire connectors to the opposite corresponding uprights.

10

In testimony whereof I hereunto affix my signature in the presence of two witnesses.
